UNITED STATES PATENT OFFICE.

ANKER S. LYHNE, OF BRIDGEPORT, CONNECTICUT.

VANITY BOX.

Application filed October 21, 1925. Serial No. 63,981.

This invention relates to vanity boxes such as are adapted to be carried in a lady's handbag, and has for an object to provide a box of this character which will be neat and attractive in appearance, which will be simple in construction, which will have a relatively large compartment for carrying a loose powder, and will be so constructed that the powder cannot pass from the container under ordinary handling but will be easily accessible in desired amounts when required for use.

With the foregoing and other objects in view, I have devised the construction illustrated in the accompanying drawing forming a part of this specification, similar reference characters being employed throughout the various figures to indicate corresponding elements. In this drawing,

Fig. 1 is a side elevation of the box in open position.

Fig. 2 is a top plan view thereof in open position.

Fig. 3 is a vertical section through the same on an enlarged scale, and

Fig. 4 is a plan and side elevation of the closure for the opening in the cover to the powder container.

The box comprises the usual body section 10 and cover section 11 hinged together at one side by the hinge 12, the lower section preferably being reduced in diameter at its upper side, as indicated at 13, so as to telescope into the cover section when the cover is closed, and it may have any usual type of catch 14 at the opposite side from the hinge. In one of the sections, preferably the lower or body section, is a container for loose powder. This container may be the lower section but preferably comprises a separate container which is inserted in this body section. As shown in the drawing this container includes a lower section 15 inserted in the body section of the box and is adapted to carry the loose powder 16. The upper open side of this container is closed by a cover 17, which preferably has a downwardly extending flange 18 telescoping in and fitting closely the walls of the container to provide a tight joint and prevent leakage of the powder from the container, the cover being preferably bent upon itself as shown at 19, to form an outwardly extending flange to engage the upper edge of the lower section of the container and limit its downwardly movement. This flange also pro-

vides convenient means for removing the cover from the container for the purpose of refilling with loose powder. As will be seen in Fig. 3 the top wall 20 of the cover is inclined downwardly toward the opening 21 in this cover, and about this opening the walls are bent downwardly to form a flange 22. The opening is closed by means of a closure 23, this closure being in the form of a metal plate having downwardly extending resilient fingers 24 which are adapted to rest on the bottom of the container and hold the closure yielding against the flange 22 to close the opening. The construction of this closure shown in Fig. 4 is the preferred construction as it is simple and can be stamped from a piece of sheet metal. It will be noted that the plate is cut inwardly from its free edge as shown at 25 for a short distance and then circumferentially for a suitable distance as shown at 26. The strip between the circumferential cut 26 and the outer periphery of the disc is then bent laterally to form the resilient fingers 24, and it will be apparent that these fingers are integral or formed in one piece with this plate, and there may be as many of these fingers as is found desirable.

In use the loose powder 16 may be placed in the container after removing the cover 17. The closure 23 is placed in the container and the cover 17 is then replaced in the container with the flange 22 engaging the top of the closure 23. It will be apparent that this will effectively close the opening 21 and the powder cannot pass from the container in ordinary handling. If, however, the top of the closure 23 is tapped lightly with a puff 27 it will be depressed somewhat allowing a small amount of powder to pass from the container onto the top of this plate 23, and this passage of the powder will be assisted by the flow of air from the container as the closure is depressed. The downwardly extending flange 22 provides a depression in the cover to hold this loose powder until it is taken up by the puff. The downwardly inclined top wall 20 of the cover will cause any powder which may get on this wall to flow back to the opening 21 instead of being spilled out over the side of the box. It also provides a depression to receive and hold the puff 27 in position for immediate use when required. The cover section 11 may be provided with the usual mirror 28.

It will be apparent from the foregoing de-

scription that the box is extremely simple in construction and will carry a relatively large amount of loose powder. It will also be apparent that the container for the powder is effectively closed against accidental spilling of the powder in carrying the box, but that it is always easily accessible in the required amounts when desired. This is a great advantage over the compacts generally used as they are liable to become broken causing them to separate from their mountings, and furthermore, it is not always possible to secure the desired brand or quality of powder in the compact form.

15 Having thus set forth the nature of my invention, what I claim is:

1. In a vanity box, cover and body sections, one of said sections including a loose powder container, a cover for said container having an opening, and a closure for said opening comprising a plate disconnected from the cover provided with integral, downwardly extending resilient fingers to engage the bottom of the container and yieldingly hold the closure over the opening, said fingers being arranged to extend transversely of radial lines from the center of the plate and spaced from this center.

2. In a vanity box, cover and body sections, one of said sections including a loose powder container, an annular cover for the container having an opening, the walls of the cover being inclined inwardly from adjacent its outer periphery to said opening, and a closure for said opening comprising a plate free of the cover provided with integral downwardly extending resilient fingers to engage the bottom of the container and yieldingly hold the closure over the opening, said fingers comprising sections cut from the plate and extending in a direction circumferentially of the plate.

3. In a vanity box, a container for loose powder, a cover for said container having an opening, a closure for said opening comprising a plate free of the cover having three or more downwardly extending re-

silient fingers to engage the bottom of the container and yieldingly hold the closure over said opening, said fingers being arranged to extend transversely of radial lines from the center of the plate and substantially equally spaced from each other.

4. In a vanity box, body and cover sections including a container for loose powder, a cover for the container having an opening, and a closure for said opening comprising a metal plate provided with a plurality of spring fingers cut from the plate and integral therewith extending downwardly therefrom to react with the bottom of the container and yieldingly hold the closure over said opening.

5. In a vanity box, hinged cover and body sections, a loose powder container in the body section, a cover for said container having an opening with the walls of the cover inclined downwardly to said opening and having a downwardly extending flange about said opening to provide space for a puff between the cover and the cover section, a closure for said opening comprising a plate disconnected from the cover and extending outside said flange, and resilient supporting means for the plate to yieldingly hold the plate against the under side of the cover and over said opening, comprising fingers cut from the plate outside the flange and extending circumferentially thereof, said fingers being integral with the plate.

6. In a vanity box, a container for loose powder, a cover for the container having an opening, and a closure for said opening comprising a plate cut inwardly from its periphery at a plurality of spaced locations and then circumferentially from said cuts at a distance from said periphery, the portions outside said latter cuts being bent laterally to provide spring fingers to support the plate and yieldingly hold it in position over the opening in the cover.

In testimony whereof I affix my signature.

ANKER S. LYHNE.
